DOWNDRAFT PILOT FOR VAPORIZING OIL BURNERS

Filed Feb. 24, 1948

UNITED STATES PATENT OFFICE

2,549,067

DOWNDRAFT PILOT FOR VAPORIZING OIL
BURNERSHarold B. Donley, Columbus, Ohio, assignor to
Columbus Metal Products, Inc., Columbus,
Ohio, a corporation of Ohio

Application February 24, 1948, Serial No. 10,257

3 Claims. (Cl. 158—91)

1

This invention relates to a pilot light, and particularly to a pilot light suitable for use with a burner. In the particular form here shown the pilot light is applied to a liquid fuel burner.

Another object of this invention is to provide a pilot light suitable for use with the so-called "pot type" burner.

A further object is to provide a pilot light of the type indicated which is permanently located within the pot or main burner and which remains in place at all times.

Another object is to provide a pilot light through which all the fuel used in the main burner is passed in liquid or vaporized form.

Another object is to provide a pilot structure in which a substantial area of the pot bottom is maintained adequately heated.

Another object is to provide a pilot structure in which there is a minimum of smoking or carbon deposit or distillation.

Another purpose is to provide a pilot structure with a low "turn down."

Other purposes will appear from time to time in the course of the specification and claims.

Figure 1 is a vertical section on the axis of the pot;

Figure 2 is a section on the line 2—2 of Figure 1;

Figure 3 is a section on the line 3—3 of Figure 1.

Like parts are indicated by like characters in the specification and drawings.

As shown, the burner comprises an outer wall or jacket 1 which may be closed at its bottom by a member 2 provided with an opening 3. A burner pot 4 is positioned within the member 1 and is supported on a ledge 5 fixed to the member 1. A flame plate 6 may be positioned over the pot 4. This plate is provided with an opening 7 and may have a centering annular enlargement 8. The pot 4 is provided with one or more groups or rows of perforations 9 positioned in its walls, and with a row or group of upwardly inclined perforations 10 positioned toward its upper edge. The pot 4 is closed by a plate or member 11 which, as shown, is integral with the remainder of the member 4. The member 4 may be provided with a lateral flange 12 which rests upon the ledge 5 and beneath the flame ring 6. A fuel inlet 13 is formed of a pipe or conduit which conducts fuel from any source to the interior of the pilot and thence to the interior of the pot.

The pilot structure herein shown may include a circumferential and generally cylindrical or partially cylindrical wall 20. This wall may at

2

its ends, as at 21, butt against the opposed inner surface of the pot wall 4. If necessary, any suitable sealing means, not herein shown, may be used. The pilot housing or pilot piece is shown as having a closed top wall 22, upwardly formed at one point to constitute a duct 23 through which air from within the outer jacket 1 may pass through the aperture 24 in the pot wall 4.

Within the pilot housing thus formed, I provide an inner top wall 25 which has a downwardly extending and general cylindrical wall 26 connecting to the circumferential outer wall 20 by the upwardly and outwardly wall portion 27. The wall 26 does not constitute a complete cylinder but terminates at its ends with connecting walls 28 which are shown as extending to and abutting against the inner surface of the pot side wall 4. It will be understood that the parts above described may be connected to each other and to the pot in any suitable manner. I illustrate the pilot piece, for convenience, as formed of an inner and outer piece connected by the spacing stud 29 and the securing screw 29a. But this is merely an example of one method of forming and assembling the pilot piece. Nor do I wish to be limited to any particular means of or method for securing the pilot piece, as a whole, in relation to the pot.

In the use of the device, the fuel supplied for the pot is delivered along the supply duct 13. The fuel then flows across the bottom 11 of the pot. Primary air for the mixture flows downwardly through a plurality of primary air inlets 30 which are shown as generally vertical inlets or passages in the inner horizontal wall 25. These apertures deliver air downwardly toward the bottom of the pot and into the vaporized volatile fuel. The primary mixture is preferably not completely combustible being heavily on the rich side, so far as the fuel component is concerned. This mixture flows outwardly and moves towards the outlet openings or notches 31 formed in the lower edge of the circumferential wall 20. I provide secondary air supply means for the rich mixture, in the form of secondary air inlets 32 which may be conveniently formed in the wall 27 and are preferably inclined downwardly and outwardly in relation to the portion or space of the pilot piece. I find it advantageous, in some circumstances, to align the secondary air inlets 32 with the solid parts 33 of the lower edge of the wall 20, but this is a matter of choice and need not in all cases be done.

I illustrate also an outer wall or circumferential baffle 35. This may be spaced somewhat out-

3

wardly from the circumferential wall 20 but is preferably substantially shorter than the wall 20. The baffle 35, however, may be omitted if desired.

It will be realized that the details of the pilot structure can be widely varied. For example, any suitable means may be employed for spacing or positioning the pilot piece in relation to the pot, and for spacing the outer wall or baffle 35 in relation to the pilot piece. For example in Figure 3, I illustrate connecting wall or lugs 36, which may be used if desired, and may extend between the walls 20 and 35, or may be used, as spacers, and in that event may be secured to either the wall 20 or the wall 35.

Whereas I have described and shown a practical and operative device, nevertheless many changes in the size, shape, number and disposition of parts may be made without departing from the spirit of my invention. I therefore wish my description and drawings to be taken as in a broad sense illustrative or diagrammatic, rather than as limiting me to my precise showing.

The use and operation of my invention are as follows:

In the particular from herein shown, the pilot piece or housing is mounted within a pot type or vaporizing burner adapted for the combustion of liquid, hydrocarbon fuels. This burner itself may be mounted in many different sorts of housings and associations. The one shown herewith is merely typical of such mountings. Air for the main pot 4 enters through the opening 3 in the plate 2 and passes upwardly about the space bounded by the members 1 and 4. This air passes inwardly through the openings 9 and may be considered the primary air. It mixes with liquid fuel present in the pot 4 and causes a primary vaporization. This results in a rich mixture which rises and into which secondary air is discharged through the upwardly inclined openings or perforations 10. When sufficient fuel is present, combustion occurs in the pot 4 above the bottom, and final combustion occurs toward the top of the pot. The flame produced may extend upwardly through the opening 7.

An important factor in burners of the above type is an adequate pilot means which permits a low turn down and which avoids the formation or deposit of carbon or products of distillation in the pilot piece or elsewhere in the pot. In the pilot piece herein shown I provide a space X, which is surrounded by and defined by the pot bottom 11, the pot side wall 4, the inner pilot wall 25 and the circumferential pilot walls 26 and 27. Into this space, through the supply duct 13, the entire supply of fuel for the burner flows. It will be realized, however, that if I desire, I may use more than one supply duct and may, in that event, have some main fuel supply means other than the duct which supplies the pilot piece.

The liquid fuel, which is delivered at various volumes by any suitable control means not herein shown, such as a conventional float valve, flows open and is evaporated upon the bottom of the pot. I find it advantageous to direct the primary air supply directly downwardly into the space X and against the mixture burning therein. At minimum rates of flow the combustion may take place solely within the space X, but I find it preferable to maintain a fuel flow, even during pilot use, effective to cause the movement of jets of flame outwardly through the notches or openings 31, and along the bottom of the pot. Where

4

the wall 35 is omitted, these jets may form what is in effect a star of flame, covering a substantial part of the bottom of the pot. Under some circumstances, I find it advantageous to provide the circumferential baffle 35 which somewhat reduces that part of the pot area over which the flame delivers, but which maintains clean and otherwise advantageous combustion conditions.

The fact that the flame passes outwardly through a plurality of apertures 31, formed in the lower edge of the wall 20, makes acute sealing of the lower edge of the wall 20 in relation to the bottom uncritical.

I claim:

1. In a burner having a pot which includes a bottom wall, a side wall having openings therein and a liquid fuel supply, a pilot structure having wall portions defining, with the bottom of the burner, a mixing chamber closed at the top and sides and in communication with the supply of liquid fuel to the burner, and having additional wall portions which define, with the mixing chamber wall portions, a plenum chamber having a portion overlying the mixing chamber and a second portion surrounding an upper, inner part of the mixing chamber, said surrounding portion extending substantially downwardly and terminating adjacent but above the bottom of the pot, said pilot structure having an air inlet to said plenum chamber registering with an opening in the side wall of said pot and adapted to receive an air supply therethrough, the pilot structure having a plurality of flame outlets located in the lower edge of said mixing chamber, that wall portion of the pilot structure which defines the bottom of the surrounding portion of the plenum chamber having therein secondary air inlet apertures adapted to direct downward jets of air adjacent said flame outlets, that portion of the pilot structure wall separating the upper, inner part of the mixing chamber from the overlying portion of the plenum chamber having primary air inlet apertures therein adapted for the direction of air downwardly into the mixing chamber at points remote from the flame outlet.

2. The structure of claim 1 characterized by and including the provision of the secondary air inlet apertures in staggered relation with the flame outlets about the lower edge of the pilot structure.

3. The structure of claim 1 characterized by and including an exterior baffle upwardly extending from the bottom of the burner pot, and means for positioning it closely about the pilot structure and substantially normal to the axis of the flame outlets.

HAROLD B. DONLEY.
